FIG. 5. 40 25

UNITED STATES PATENT OFFICE.

WINFRED W. HARRIS, OF MELROSE, MASSACHUSETTS, ASSIGNOR TO DOEHLER DIE-CASTING CO., A CORPORATION OF NEW YORK.

SHUTTLE.

Application filed April 15, 1924. Serial No. 706,655.

To all whom it may concern:

Be it known that I, WINFRED W. HARRIS, a citizen of the United States, residing at Melrose, in the county of Middlesex and State of Massachusetts, have invented certain new and useful Improvements in Shuttles, of which the following is a full, clear, and exact description.

This invention relates to shuttles and particularly to the body portions thereof. Heretofore the body portion of a shuttle has usually been formed from a single block of wood and the ends of the wooden body have been provided with metal tips to receive the blows of the pickers. Inasmuch, however, as the woods most satisfactorily for shuttle bodies are becoming very scarce and expensive, attempts have been made to develop satisfactory shuttle bodies in which some or all of the wood is replaced by other material such, for example, as a metal or an alloy. Such shuttle bodies should be comparatively light to enable them to be operated satisfactorily by shuttle-picking mechanism of looms now in use and should at the same time be of sufficient strength to withstand the blows of the pickers.

An object of this invention is to provide an improved shuttle body to replace the shuttle bodies formed from single blocks of wood, and which will be strong, durable, relatively inexpensive, and capable of meeting all requirements to which it may be subjected in practice. Other objects and advantages will be apparent from the following description of an embodiment of the invention, and the novel features will hereinafter be particularly pointed out in the claims.

The invention resides in the novel shuttle body, and in the manner of assembling and securing the component parts.

In the accompanying drawings:—

Fig. 1 is a top view of a shuttle body embodying the preferred form of the invention;

Fig. 2 is a longitudinal section of the

same taken substantially along the line 2—2 of Fig. 1;

Fig. 3 is a transverse section of the same, taken substantially along the line 3—3 of Fig. 2;

Fig. 4 is a transverse section of the same, taken substantially along the line 4—4 of Fig. 2;

Fig. 5 is a front elevation of the end of the shuttle provided with the thread eye; and

Fig. 6 is a detail sectional view of the shuttle showing the manner in which one end of the shuttle is secured to one of the side walls.

In the illustrated embodiment of the invention, metal head ends 10 and 11 are secured to the ends of side walls or bars 12 of wood, fibre or other suitable material, which are lighter than if made of metal and are adapted to be acted on directly by shuttle-check devices acting frictionally to retard the shuttle as it enters a box at either end of the lay. Both of the ends 10 and 11 may be provided with hardened tips 13 and with transverse wear-resisting plugs 14 of fibre, wood, raw hide or material other than metal, the plugs being held in place by friction and also by pins 15. The ends 10 and 11 are also provided at their lower faces with longitudinal grooves 16 and 17 respectively.

The end 11 is provided with a recess 18 to receive a device (not shown) for supporting a bobbin or the like between the side walls 12 and with a bolt or screw 19 for securing such supporting device in position. Usually the bobbin-supporting device is a pressed metal attachment for receiving the fixed end of the bobbin and allowing the transfer of the bobbin when the weft breaks or approaches exhaustion. Preferably the slotted head of the bolt 19 is seated in a cup washer 20 in a countersink on one side of the end 11 and threaded into the base of another cup washer 21 in a countersink at the opposite side of the end 11.

The end 10 of the shuttle body is provided with a lateral thread eye 22 substantially in alignment with a groove 23 extending substantially longitudinally of the shuttle, 5 to prevent unnecessary wear of the thread drawn outwardly from the thread eye 22 in the operation of weaving. In threading the shuttle the thread is drawn forwardly through a central recess 24 in the head 10 10 and then downwardly through a slot 25 into the thread eye 22. It has also been found desirable to provide the end 10 with an opening 26 connecting the recess 24 with the groove 16, with shallow segmental cut-outs 15 27 at opposite sides of the recess 24, and with a shallow longitudinal groove 28 extending substantially from the recess 24 to the adjacent tip 13. It should be understood that in practice, an automatic threader (not shown) is secured in the central recess and 20 that the head 10 is constructed to cooperate with such a threader.

Obviously the stresses resulting from checking the shuttle by frictional engagement with the shuttle checks at opposite 25 ends of the lay, and from the blows of the picker-sticks tend to loosen the connections between the side walls 12 and the ends 10 and 11. Such connections should, therefore 30 be made very strong.

To secure the side bars 12 to the metal end 11, the corresponding ends of the bars 12 are cut away at each edge as indicated by the lines 29 in Figure 2 and the reduced 35 portions 30 so formed are inserted into recesses 31 converging towards the adjacent tip. As seen in Figs. 1 and 3, the countersinks receiving the cup washers 20 and 21 are continued into the reduced portions 30 40 so that the cup washers tend to lock the reduced portions 30 in the recesses 31. Inasmuch as the bolt 19 must pass through the reduced portions 30 and the bobbin-holding device (not shown) to be placed in the recess 45 18, all of such parts must be assembled before the insertion of the bolt and will be held in position thereby. At each side, the end 11 of the shuttle body is provided with a segment-shaped extension 32 which fits 50 closely against the adjacent side bar 12. The shape of the extensions 32 serves not only to assist in holding the bars 12 in position in the end 11 but also to prevent the thread from catching in the slots between 55 the metal and the bars 12. The bending of bars 12 as seen at the left in Figure 1 may be effected in any suitable manner, as, for example, by steaming before or after the insertion of the reduced portions 30 into the 60 recesses 31.

At their forward ends the bars 12 are provided with reduced ends 33 to be forced upwardly into converging slots 34 which are closed at the top. To secure the bars 12 65 against longitudinal withdrawal, the inner

wall of each slot is provided with ribs 35 and 36 respectively fitting into corresponding grooves in the corresponding side bar. As indicated in Figures 1 and 4 the shape of the ribs 36 conforms in general to the shape 70 of the segmental cut-outs 27 so as to leave walls between such cut-outs and the upper parts of the slots 34.

As an additional means of securing the bars 12 to the end 10, provision is made of a 75 bolt or screw 37 having its slotted head seated in a cup washer 38 in a countersink extending from the side of the end 10 into the adjacent reduced portion 33, and its opposite end threaded into the base of a cup 80 washer 39 in a countersink extending from the side of the end 10 into the adjacent reduced portion 33. The bolt 37 is also used to secure an automatic 85 thresher in the end 10. It will be evident that the cup washers 38 and 39 will hold the bars 12 in position in the end 10 during the insertion of the automatic thresher and the bolt 37.

As shown in Figures 2 and 5, the sides of 90 the end 10 are bevelled so that they are longer at the top than at the bottom and consequently avoid the possibility of the thread catching in the slot formed at this point. Such a slot is so inclined to the line followed by the thread that the thread is not likely to catch in it.

To obviate unnecessary wear of the head 10 at the shuttle eye 22, provision is made of 100 wear pins 40 on opposite sides of the slot 25.

It will be obvious that various changes in the details herein described and illustrated for the purpose of explaining the nature of the invention, may be made within the principle and scope of the invention as expressed 105 in the appended claims.

I claim:

1. A shuttle body comprising metal end sections, side bars connecting said sections, one of said sections having sockets in its inner end adjacent opposite sides thereof diverging toward the opposite end section, said side bars being anchored in said diverging sockets and sprung at their free ends toward one another before connection to the other end section.

2. A shuttle body comprising metal end sections, each section having sockets in its inner end adjacent opposite sides thereof, the sockets of one section diverging toward the opposite end of the body, side bars inserted in said diverging sockets, sprung at their free ends toward one another, and anchored in the sockets of the other end section, and means countersunk into the ends of the side bars within the diverging sockets for locking the side bars therein.

3. A shuttle body comprising two heads and side bars to connect said heads, one of 130

said heads and the corresponding ends of the bars being shaped to compel their assembly by relative movement longitudinal with respect to the side bars, and the other head 5 and the corresponding ends of the side bars being so shaped as to compel their assembly by relative movement transverse with respect to said side bars.

4. A shuttle body comprising metal end 10 sections, one section having sockets in its inner end and diverging toward the opposite end of the body, and side bars anchored at one end in said diverging sockets and at their other ends sprung toward one another 15 and anchored to the other end section.

5. A shuttle body comprising metal end 20 sections, side bars connecting said sections, one of the end sections having sockets in which the side bars are received, said one section having openings into said sockets in 25 directions transverse to the side bars, and removable means in said openings and countersunk partially into said side bars to lock the latter within the sockets.

25 6. A shuttle body comprising metal end sections, side bars connecting said sections, each end section having sockets in which the ends of the side bars are received, the 30 sockets of one end section opening from the inner end of the section, extending in a direction lengthwise of the body, and diverging toward the other end of the body, the side bars after insertion therein being 35 sprung toward one another at their free ends and inserted into the sockets of the other end section, the latter sockets opening from the inner ends and also laterally to permit of the lateral entrance of the side bars therein.

40 7. A shuttle body comprising metal end sections, side bars connecting said sections, each end section having sockets in which the ends of the side bars are received, the 45 sockets of one end section opening from the inner end of the section, extending in a direction lengthwise of the body, and diverging toward the other end of the body, the side bars after insertion therein being 50 sprung toward one another at their free ends and inserted into the sockets of the other end section, the latter sockets opening from the inner ends and also laterally to permit of the lateral entrance of the side bars therein, said sockets with the lateral 55 openings and the inserted ends of the side bars, having cooperating ribs and grooves extending transversely of the length of the side bars for anchoring the side bars therein.

8. A shuttle body comprising a front end 60 provided with a thread eye, side bars connected with said front end and cut away at their rear ends at both top and bottom to form reduced portions, a rear end having a central recess to receive a bobbin 65 holder and recesses at opposite sides of the

central recess to receive the reduced rear portions of said bars, said rear end of the shuttle body and said reduced portions having aligned counter-sinks extending from opposite sides of said rear end into said 70 reduced portions, a washer in one of said countersinks lying partly in said rear end and partly in the corresponding reduced portion, a nut correspondingly located in the other countersink, and a bolt passing 75 through said washer and threaded into said nut.

9. A shuttle body comprising a rear end 80 to receive a bobbin holder, side bars attached to said rear end and having at their forward ends reduced portions with transverse grooves, and a front end having vertical slots to receive said reduced portions transversely and ribs to fit into said grooves.

10. A shuttle body comprising a rear end 85 to receive a bobbin holder, side bars attached to said rear end and having at their forward ends reduced portions with transverse grooves, and a front end having vertical slots closed at the top and open at the 90 bottom, to receive said reduced portions transversely and ribs to fit into said grooves.

11. A shuttle body comprising a rear end 95 to receive a bobbin holder, side bars attached to said rear end and having at their forward ends reduced portions with transverse grooves in the inner faces thereof, and a front end having a central threading opening and vertical slots to receive said reduced portions transversely and ribs to fit 100 into said grooves, one of said ribs at each slot extending into the slot to such an extent as to provide a wall of sufficient thickness between the slot and the central threading opening.

12. A shuttle body comprising a rear end 110 to receive a bobbin holder, side bars attached to said rear end and having at their forward ends reduced portions with transverse grooves and a front end having vertical slots closed at the top and open at the bottom to receive said reduced portions transversely and ribs to fit into said grooves, the sides of the front end being bevelled at 115 their edges so as to be longer at the top than the bottom, and to form with the side bars joints such as to avoid catching the thread.

13. A shuttle body comprising side bars 120 of fibrous material; a thread-delivery head attached to said side bars at one end, and a bobbin holding head having recesses to receive the ends of said bars and segment-shaped extensions to fit closely against the outer faces of said bars, the convex forward edges of said extensions assisting in preventing relative displacement of the bars and head and serving to prevent catching of the thread.

14. A shuttle body comprising metal end 130

sections, each section having sockets opening from the inner ends and extending in a direction lengthwise of the body, side bars received in said sockets and connecting said end sections, a bolt passing through each end section including the sockets thereof and the inserted ends of the side bars for anchoring the side bars therein, said bolt

having at its ends enlarged sections countersunk partially into the ends of the side bars ¹⁰ which are within the sockets for preventing tearing of the bolt through the side bars.

In witness whereof, I hereunto subscribe my signature.

WINFRED W. HARRIS.
